UNITED STATES PATENT OFFICE.

HERMAN J. LOMBAERT, OF PHILADELPHIA, PENNSYLVANIA.

IMPROVED MODE OF CONSTRUCTING AND APPLYING RAILS TO RAILROADS.

Specification forming part of Letters Patent No. 35,879, dated July 15, 1862.

To all whom it may concern:

Be it known that I, HERMAN J. LOMBAERT, of the city of Philadelphia, in the State of Pennsylvania, have invented a new and useful Improvement in the Construction and Application of Rails for Railroads; and I do hereby declare that the following is a full and exact description of the same, reference being had to the accompanying drawings, making a part of this specification, and to the letters of reference marked thereon.

It is well known to all persons experienced in railroad construction, management, and repairs that all the systems of railway-track construction on which steam is used as the motive power have thus far failed in securing a continuous surface of uniform elasticity and strength.

The combination which I have devised and herein described, it is believed, will go far to secure these important and very desirable results, and without any considerable increase in the original cost of construction.

The nature of my invention consists, substantially as hereinafter described and specified, in dividing the metal used in making the ordinary single-bar rail into two separate or distinct parts, which, for clearness in description, I term, respectively, the "wearing-rail" and the "supporting-rail," and combining them together in horizontal planes or parallel with each other by means of intermediating blocks or plates, in combination with clamping-hooks or their equivalents arranged and secured at equal distances apart from each other and in certain relation to the positions of the supporting cross-ties or ground-sills to which the rails are applied, for the purpose of producing a compound rail that will be at least equal in strength to the said ordinary single-bar rail as the same is now laid to form a track, and a track-surface having a uniform elasticity and strength throughout under the ordinary loads now carried on railroads by steam as the motive power; and the nature of my invention also consists in the mode, hereinafter described and specified, of securing the joints which occur at the abutting or contiguous ends of the wearing-rails, for the purpose of insuring at these parts of the track the same general elasticity and at least the same equality of strength which are characteristics of the other portions of the track.

In the drawings, Figure 1 is a side elevation of a portion of a track, showing the general construction and application of my invention, and Fig. 2 a plan view of the upper side of the supporting-rail thereof, both figures being drawn to a scale of about one-twelfth of the full size; Fig. 3, an end view of the portion of the track of full size cut vertically through the parts indicated by the dotted line V of Fig. 1; Fig. 4, an end view of like size of the same portion of the track cut vertically through the parts indicated by the dotted line W of Fig. 1; Figs. 5 and 6, plan views of the upper and under sides, respectively, of the intermediating blocks or plates with clamping-hooks thereon, and Fig. 7 a like view of the upper side of the intermediating blocks or plates used in securing the joints formed by the abutting or contiguous ends of the wearing-rails, the three last-mentioned figures being drawn to a scale of about one-fourth of the full size, like letters indicating the same parts when in the different figures.

A is the wearing-rail; B, the supporting-rail; C, the intermediating blocks or plates; D, the clamping-hooks, and E the ordinary cross-ties or ground-sills.

Any of the flange-rails now in general use on steam-railroads are applicable to this system, and a rail of the form shown in Figs. 3 and 4, and weighing from thirty to forty pounds per lineal yard, which is the size intended to be represented, if made of the best quality of iron or of steel, will be about equal in strength to the ordinary fifty-six or sixty-four pound rail as the same is now laid.

The supporting-rails B each consist of wrought-iron rolled into a length equal to that of the wearing-rail A and a width at its upper side that will be at least equal to the width of the base of the said rail A. Its upper side presents a flat surface, with the exception of a series of small protuberances, b', which will be hereinafter described, its right and left sides being recessed so as to produce the nearly-vertical planes b¹ b⁵, and also beveled edges b² b⁴, that will correspond with the beveled edges a' a' of the base of the wearing-rail A, substantially as shown in the transverse sections, Figs. 3 and 4, while its remaining under portion may be either flat or rigid and grooved, so as to secure the greatest strength from the same amount of metal. A central longitudinal line

of through-holes, b^3 , (see Figs. 2 and 4,) is made in the said rail B, for the purpose of admitting the spikes or bolts F, whereby it is fixed to the cross-ties E, as will hereinafter be more fully described. These holes b^3 are made at equal distances apart, corresponding with the distance determined upon from center to center of each of the blocks or plates C interposed between the wearing-rail A and the supporting-rail B, as indicated in Fig. 1. The weight of this supporting-rail B of the size and form shown in Figs. 3 and 4 is estimated to be about thirty pounds to the lineal yard.

The intermediatelying plates C are also each made of wrought-iron, and have their top and bottom surfaces parallel to each other, are of the same thickness, and present at one end two or more clamping lips or hooks, D, which will clasp, respectively and simultaneously, corresponding portions of one edge a' of the base of the wearing-rail A and one edge b^2 of the supporting-rail B when the said plates or blocks are placed across between the said rails A and B and drawn toward the opposite edges a' b^2 of the latter by means of the respective double hooks D', which double hooks are also made of wrought-iron and formed to clasp, respectively and simultaneously, corresponding portions of the said opposite edges of the rails A and B when inserted into the oblong holes c', which are made for the purpose through the said plates or blocks, and their beveled hooked ends forced tightly upon the said beveled edges a' b^2 of the rails A and B by driving the wedge-keys G downward, thus forcing the different parts together into the respective rigid positions indicated in Figs. 3 and 4.

Each of the plates C should be about three-quarters of an inch thick and (except where a joint, a^2 , occurs from the abutting or contiguous ends of any two wearing-rails) about three inches wide. The under side of each plate C has a shallow cavity or indentation, c', (see Figs. 3 and 5,) which receives one of the protuberances b' of the supporting-rail B when the said plate is laid in its proper position across the said rail, as before described, the said indentations c' being made oblong in the moving direction of the plates for the purpose of allowing the same to be the more readily applied, and afterward, in forcing the respective hooks D D' toward each other in clamping the rails A and B together with the said plates C between, allowing the latter to slide across between them sufficiently for the purpose. The protuberances b' of the rail B are arranged at equal distances apart and in such relation to the bolt-holes b^3 that the blocks or plates C shall be equidistant from their nearest bolt-holes when the said plates are placed over their respective protuberances, as seen in Figs. 1 and 2.

In applying these compound rails to the ordinary cross-ties, E, so as to produce the track required, the cross-ties are first "boxed out" or recessed across their upper sides in such a

manner as to adapt them to receive accurately in the said recesses the respective crossing portions of the supporting-rails B at the required distance apart, the flat upper surface of each coming flush, or nearly so, with the upper sides of the said cross-ties, or in the same general plane with their upper sides, substantially as indicated in Figs. 1, 3, and 4, thus effectually preventing the rails of the track from any probability of separating from each other or moving laterally on the cross-ties. The supporting-rails B are next permanently secured in the said recesses of the cross-ties by means of appropriate spikes or bolts, F, substantially as represented in the same figures. The plates C are now placed regularly along upon the supporting-rail B, with their respective cavities or indentations c' directly over the protuberances b' , and consequently their lower hooks, D, in conjunction with the one edge b^2 of the supporting-rail B, and then the wearing-rails A laid directly upon them, with one edge a' of their respective bases slipped within the upper hooks, D, of the plates. The double-hook pieces D' are now respectively applied through the holes c' in the plates and their respective wedge-keys G then inserted behind them and driven down until the rails A and B are rigidly clamped together, as before described, with the plates C between, substantially as represented in Figs. 1 and 3.

For the purpose of preventing the wedge-keys G from being worked loose by the tremor produced in the track by the passage of trains, and also for the purpose of compensating for any differences in the sizes of the keys G or holes c', a strip of pliable metallic plate, H, is intended to be inserted with each key, and its upper end, after the key is driven down firmly, bent over upon the upper end of the latter, and its lower end bent outward or upward against the under side of the projecting end of the plate C, substantially as seen in Figs. 3 and 4.

The wearing-rails A are also so laid upon the blocks or plates C that their abutting or contiguous ends shall bring the joint-lines a^2 each at a point midway between the centers of the two adjacent cross-ties, and therefore also midway between the two adjacent protuberances b' of the supporting-rail B, and for the purpose of supporting in the most effectual manner the said abutting or contiguous ends of the rails A a longer single plate, C², is substituted for the two which would otherwise be employed apart between the said two cross-ties. If the regular distance apart from out to out of any two of the smaller plates C be eighteen inches, the plate C² for the joint a^2 is made eighteen inches long, as seen in Fig. 7, and its hooks D and draw-holes c' arranged so that there will be produced central lips or hooks D D' on its upper side, each of sufficient width to clamp simultaneously the corner edges of both of the abutting or contiguous

ends of the bases of the wearing-rails A, substantially in the manner indicated in Figs. 1 and 4.

In the use of this invention it will be seen that although substantially the same quantity of metal that is required to produce the ordinary single-bar rail of sixty-four pounds to the lineal yard is divided into the two distinct rails A and B, the former weighing about thirty-five pounds and the latter, say, thirty pounds to the lineal yard, yet the relative positions of the two said parts A and B, constructed and combined together rigidly by

means of the clamps and intermediating plates arranged at the regular distances apart described, are such that there will be afforded a supporting strength in the combination which will be at least equal to that of a single-bar rail of like weight as now laid, and at a cost of production but little exceeding that of the latter, and with but about half the weight subjected to the wear and tear of the rolling-stock.

It will also be seen that inasmuch as there does not exist in this system or mode of constructing and applying track-rails any direct connection between the wearing-rail A and the ground-sills, or, in other words, that as the said rail A is supported directly upon a series of blocks or plates arranged upon the supporting-rail B, so as to be at equal distances apart and also equidistant from their nearest ground-sills, as seen in Fig. 1, there will be afforded uniform elasticity and strength throughout the whole length of the same under the ordinary loads now carried on railroads, and this even if solid stone blocks be substituted for the ordinary wooden ground-sills or cross-ties, and that, the two said rails A and B being rigidly combined together by means of strong clamps in combination with the intermediating plates C, as described, while the whole is secured to the cross-ties by sinking and bolting or spiking the said supporting-rail therein in the manner described, the liability to displacement or the separation of the rails from each other incident to the ordinary single-bar rail track, and the consequent danger and expense incident to the use of "chairs" and other similar devices hitherto depended upon for securing the said ordinary rails to the cross-ties or ground-sills, are entirely obviated.

Another feature of peculiarity and importance will also be seen in the appropriateness of the different parts described to the production of a secure and reliable joint at the abutting or contiguous ends of the wearing-rails.

The contiguous ends of the supporting-rails b' b' should be arranged to come between any appropriate two of the plates or blocks C which are intermediate between their adjacent cross-ties, as seen in Fig. 1, because the pressure of a locomotive and train of loaded cars in rolling over the track will necessarily be transmitted to the cross-ties in succession through those blocks or plates only which are adjacent to the said cross-ties, and for the same rea-

son those other portions of the supporting-rail B which come between any two of the blocks or plates that are between the cross-ties, excepting, of course, the portions which are directly beneath the abutting or contiguous ends of the wearing-rails A, and in contact with the longer plate C, might, perhaps, be safely dispensed with for the sake of economy in material; but the saving of iron that would be effected by thus cutting the said supporting-rail B into short sections for separation, compared with the advantages arising from the use of a continuous supporting-rail, as shown in Fig. 1, especially in the greater facility afforded for their alignment when laying them upon the cross-ties, is so unimportant as to render the latter construction far preferable. In fact, so little will be the skill required in laying down this compound rail—the supporting-rail B being continuous—that any unskilled labourer, after a little practice, will be competent to the work, and any subsequent changes of any of the parts or reversions and renewals of the wearing-rails A that accident or long service of the track may render necessary will be as easily accomplished.

In the construction of my invention I wish it to be distinctly understood that I do not intend to confine myself to the particular form shown in the transverse section for the supporting-rail B, except in so far as the same is provided with suitable side edges, b' b', for the application of any suitable clamping-hooks, the said edges projecting beyond a deeper middle portion having a nearly vertical plane, b', on each side for preventing its having any lateral motion when let into the cross-ties, as described, the series of bolt-holes b'', for securing it to each of the cross-ties at the equal distances apart specified, and the series of protuberances b', or their equivalents, for indicating and maintaining the position of the blocks or plates C, as described, because the required strength and elasticity which are afforded by the supporting-rail B when constructed as described can be attained by making its transverse section to present either the form indicated by the dotted lines 1 1 in Fig. 3 or that indicated by the dotted lines 2 2 in Fig. 4, using in the latter form larger bolts for fastening it to the cross-ties, in order to allow of their being mortised for keys, as indicated by the dotted lines 4, because the latter can in such case be more easily applied than screw-nuts, and also in such case making the beveled edges b' b' about a quarter of an inch wider, so that suitably-wide notches may be pinched out, in order that the same may serve—for indicating and maintaining the proper positions of the blocks or plates and clamping-hooks—as equivalents for the protuberances b', which of course could not be conveniently formed on such a supporting-rail. Nor is it my intention to confine myself to using the exact quantity of metal in the two rails A and B which is now used in making an equal length of the ordinary single-bar rail before referred

to, because it is manifest that either a greater or a lesser quantity will have to be used as the service required of the particular road may demand or justify, and because it is equally apparent that a wrought-iron supporting-rail of the form and weight herein described, if combined with a wearing-rail of steel of considerably less area in its transverse section than that shown in Figs. 3 and 4, would produce a like compound rail of equal strength and elasticity, and at but a little, if any, increase in the original cost of construction.

In regard to the described mode of constructing and combining the clamping-hooks D D' with the plates C it may be proper to remark that I had devised an equivalent combination for the same purpose consisting of two separate clamping-pieces, each having an upper and a lower lip or hook, like the double-hooked pieces D', and applied, respectively, over the beveled edges on each side of the rails A and B, and then drawn toward each other by means of a screw-nut on a headed bolt, the latter passing through each of the clamping-pieces and also through the regular intermediating clock or plate C, the said plate, however, being made to correspond with the width of the base of the wearing-rail A; but as this mode was found to be more costly and less reliable than the first described, having upper and lower hooks D formed permanently on one end of the plate C, the latter is preferred.

Having thus fully described my improvement in the construction and application of rails for railroads, and pointed out its superior utility, and also the different modes in which I contemplate the application of the system of construction embodied therein, what I claim

as my invention, and desire to secure by Letters Patent, is—

1. A compound rail for railroads, consisting of the two parts A and B, the intermediating blocks or plates C, and the clamping-hooks D D', the same being arranged and combined together in relation to each other and to the positions of the supporting cross-ties or ground-sills, substantially as described and set forth, for the purposes specified.

2. Securing the joint which occurs at the abutting or contiguous ends of the wearing-rails A by means of an intermediating plate, C, arranged midway between the adjacent cross-ties or ground-sills and directly beneath the said joint, the said plate being rigidly clamped between the rail B and the ends of the rails A, all substantially in the manner described and set forth.

3. Making the supporting-rail B to have the nearly vertical planes b¹ b² along its recessed sides, and the beveled edges b³ b⁴ projecting therefrom, substantially as described and set forth, for the purposes specified.

4. Making the said supporting-rail B to have the central series of bolt-holes, b⁵, arranged at the equal distances apart described and set forth, for the purpose specified.

5. Making the said supporting-rail B to have the series of protuberances b' or their equivalents arranged at the equal distances apart described, and also in the relation to the bolt-holes b⁵ described, for the purposes specified.
